UNITED STATES PATENT OFFICE.

DAVID HELLER, OF BALTIMORE, MARYLAND, ASSIGNOR TO A. WEISKITTEL & SON CO.,
OF BALTIMORE, MARYLAND.

DESIGN FOR A SOIL-PIPE FITTING.

45,301.

Specification for Design.

Patented Feb. 24, 1914.

Application filed May 23, 1913. Serial No. 769,496. Term of patent 3½ years.

To all whom it may concern:

Be it known that I, DAVID HELLER, a citizen of the United States, residing in Baltimore, in the State of Maryland, have invented a new, original, and ornamental Design for a Soil-Pipe Fitting, of which the following is a specification, reference being had to the accompanying drawing, forming part thereof.

Figure 1 is a side view of a fitting show-

ing my new design; and Fig. 2 is a longitudinal section of the same.

I claim:

The ornamental design for a soil-pipe fitting, as shown.

DAVID HELLER.
